Peter Meyer
BY A. F. Bourne

ATTORNEY .

UNITED STATES PATENT OFFICE.

PETER MEYER, OF NEWARK, NEW JERSEY.

DRILLING MACHINE.

Application filed July 10, 1924. Serial No. 725,137.

To all whom it may concern:

Be it known that I, PETER MEYER, a citizen of the United States, and resident of Newark, in the county of Essex and State of New Jersey, have invented certain new and useful Improvements in Drilling Machines, of which the following is a specification.

The object of my invention is to provide means to automatically feed to drilling position and to drill articles having non-circular or irregular configurations at one or more parts, my invention being particularly applicable for drilling transversely disposed holes in pins used in pianos for retaining and tuning the strings. Such pins usually have cylindrical portions and tapering square portions near one end with transverse holes drilled through flatwise surfaces on opposite sides of the pins. In accordance with my invention I provide means to automatically feed such pins, as from a supply hopper, successively to drilling position beneath a drill and to present such pins in position with one of the flat surfaces of the pins in position opposing the drill, regardless of the positions the flat surfaces of the pins may assume when they are delivered from a hopper to be fed toward the drilling position.

My invention also comprises novel details of improvement that will be more fully hereinafter set forth and then pointed out in the claims.

Reference is to be had to the accompanying drawings forming a part hereof, wherein—

Fig. 1 is a side elevation of a drilling machine embodying my invention;

Fig. 2 is a perspective view of one of the pins to be drilled;

Fig. 3 is an end view looking from the left hand side of Fig. 1;

Fig. 4 is a sectional detail;

Fig. 5 is an enlarged detail section on line 5, 5, in Fig. 1;

Fig. 6 is a detail section on line 6, 6, in Fig. 5;

Fig. 7 is a detail on line 7, 7, of Fig. 6, and

Fig. 8 is an enlarged section on line 8, 8, in Fig. 3.

Similar numerals of reference indicate corresponding parts in the several views.

The numeral 1 indicates the main frame of the machine which may be of any suitable

construction, and at 2 is a longitudinally movable drill spindle shown provided with a chuck 3 to retain a drill 4 in any well known way. The spindle 2 may be rotated by a pulley 5, belt 6 and drive pulley 7 in a well known way. The spindle 2 is rotatively mounted and is operatively connected to a sleeve 8 slidable in bearings 9 supported by the main frame in a well known way to feed the drill to and from the work. Drive pulley 7 is shown carried by a vertical shaft 10 journaled in suitable bearings on the main frame and shown provided with gear 11 in mesh with a gear 12 on drive shaft 13, which may be operated by fast and loose pulleys 14, 15, (Fig. 3), or in any other desired way. The shaft 13 is shown provided with a pulley 16 receiving a belt 17 passing over a pulley 18 secured on shaft 19 journaled on the main frame. The shaft 19 is provided with a pinion 20 in mesh with a gear 21 secured on shaft 22 journaled in bearings upon the main frame. By the belts, pulleys and gearings described the shaft 22 is rotated at the desired speed respecting the rotation of spindle 2. The reciprocations of spindle 2 are effected by means of a lever 23 pivoted on the main frame at 24 and provided with a fork at 25 receiving projections 26 on a collar 27 secured in suitable position on sleeve 8 by means of screws 28. The opposite end of lever 23 is pivotally connected with a depending link 29 that is pivotally connected at 30 with an arm 31 journaled on a stud or shaft 32 supported by the main frame. The arm 31 is provided with a projection or roller 33 cooperative with a cam 34 secured on shaft 22, and a spring 35 connected with the main frame at 36 and with link 29 at 37 resiliently retains the projection or roller 33 in cooperation with cam 34, whereby for each complete rotation of said cam the lever 23 will be rocked to feed said spindle 2 and the drill to and from the work.

The pins A to be drilled are shown of the variety having cylindrical bodies or shanks and provided at one end with flat faces *a*, shown in outwardly tapering form arranged in rectangular form, although pins having other irregular configurations may be fed and drilled, such as hexagonal and octagonal shapes, and the like. The pins are fed into a hopper 38 suitably supported on the main frame, shown having downwardly ta-

pering bottom walls 38^a, 38^b converging to a delivery guideway or passage 39 transversely disposed to receive the lowermost pin A, (Fig. 5). A slideable plate 40 is located upon the wall 38^b of the hopper and is guided to be reciprocated along said wall by means of pins or screws 41 projecting through slots 42 into wall 38^b, which pins are shown connected together by a bar 43 that is pivotally connected with a link 44. The link 44 is pivotally connected at its lower end to crank arm 45 projecting from a rock shaft 46 journaled in bearings supported by the main frame, which shaft is provided with an arm 47 shown having a roller 48 cooperative with a cam 49 on shaft 22, (Fig. 3,) whereby as said cam is rotated the slide 40 will be reciprocated to agitate the pins in the hopper to cause them to roll down through the delivery guideway or passage 39.

A transverse bar 50 is supported adjacent to the bottom of the hopper and beneath said bar a slide member or plate 51 is supported to reciprocate. Said slide member is retained by means of screws 52 entering slots 53 in said member and screwed into bar 50, (Figs. 1 and 5). The member 51 is provided with a depending rack 54 in mesh with a gear 55 secured on shaft 46, whereby as said shaft is rocked the member 51 will be reciprocated. The member 51 is operative with relation to the guideway or passage 39 and is provided with means to receive the pins A and cause them to be turned in proper position to present one of their flat surfaces beneath the drill 4 as and when such pin is fed to drilling position from the hopper. A bar 50^a adjacent to guideway 39 is suitably spaced above the underlying portion of slide member 51 providing a passageway 56 over the end portion of said member behind the side wall 50^b, (Figs. 5 and 6), for the passage of the pins A to the drilling position. Plate 50^c is secured under passage 39 and forms the bottom of passageway 56 and guides the rod 66, (Fig. 8). The bar 50^a is provided with a recess 57 in which one or more movable pin-controlling blocks 58 are located to slide laterally with respect to said pins. The blocks 58 are supported upon plate 51 and are provided with depending pins 59 operative in slots 60 in plate 51, said blocks being normally pushed toward the path of the pins by springs 61. The springs 61 are shown coiled and located in recesses 62, 63 respectively in bar 50 and blocks 58. The forward operating surfaces of the blocks 58 are beveled and inclined at 58^a, (Figs. 6 and 7), from the pin receiving sides of said blocks toward the opposite sides and preferably from the lower to the upper surfaces of said blocks, in such a manner that when a pin A is fed along plate 51 after delivery from guideway 39 toward the

blocks 58 the inclined surfaces 58^a of said blocks will engage one or another of the flat surfaces *a* of the pin to cause the pin in its progress to the drilling position to be rotated in such a manner as to present one of its flat surfaces upwardly to pass under a drill guide 64 having an aperture 64^a for guiding the drill 4, (Figs. 1 and 3). The drill guide is shown secured by screws 65 on bar 50. The outer ends of pins A rest upon support 64^b spaced below guide 64 and secured to bar 50, (Figs. 1, 3 and 8).

In order to feed the pins A successively to drilling position I provide a reciprocative rod 66 guided in bearings at 67 on the main frame, (Fig. 1), and shown provided with a collar 68 having studs 69 receiving a fork 70^a of a rock arm 70 that is secured upon shaft 32, the lower end of said arm being shown connected with a spring 71 attached to the main frame at 72. An arm 73 secured to shaft 32 is provided with a projection or roller 74 cooperative with a cam 75 secured on shaft 22, whereby when said cam rotates in the direction of the arrow, (Fig. 1), the rod 66 will be reciprocated to push the pins through guideway 39 to drilling position. When rod 66 is retracted it is withdrawn sufficiently from guideway 39 to enable the lowermost pin in the hopper to enter the guideway, and when said rod is projected forwardly for feeding a pin it will enter said guideway and retain the pins in the hopper above, and so on successively.

The operation of the parts is such that when rod 66 advances toward the drilling position it will push the lowermost pin from the hopper through the guideway 56, which pin will encounter one or both of the blocks 58 and by the sliding of the pin along the inclined surfaces 58^a the pin will be rotated as necessary to present a flat surface in drilling position under the drill. The drill will now descend to drill the hole at *a'* through the flat surfaces of the pin on opposite sides thereof, (Fig. 2). While the drilling is being performed in one pin the rod 66 will retreat to permit another pin to enter the guideway 39, whereupon the drill will rise, and when the drill has been released from the pin the slide 51 will move to the left in Figs. 3 and 5 to permit the drilled pin to drop, whereupon said slide will return to the drilling position and rod 66 will feed another pin to drilling position, and so on successively. By the means described it is merely necessary to supply the hopper with pins with their flattened surfaces in the direction of the drill, and the pins will be successively, automatically fed and drilled and deposited accurately and expeditiously.

While I have illustrated and described a practical embodiment of my invention it will be understood that changes may be

made in the details of construction set forth without departing from the scope of the appended claims.

Having now described my invention what

5 I claim is:

1. A drilling machine of the character specified comprising means to rotate and reciprocate a drill, supply means for pins having exterior flat surfaces to retain pins in any rotary position, means to feed the pins in the direction of their longitudinal axes to drilling position, and means to rotate the pins axially to present their flat surfaces in drilling position during feeding of the pins. 10
  - 15 2. A drilling machine of the character specified comprising means to rotate and reciprocate a drill, supply means for pins having flat surfaces, means to feed the pins to drilling position, and means to cause the pins to present their flat surfaces in drilling position comprising one or more movable blocks having an inclined surface to encounter the flat surfaces of the pins to rotate them into drilling position. 20
  - 25 3. A drilling machine of the character specified comprising means to rotate and reciprocate a drill, supply means for pins having exterior flat surfaces to retain pins in any rotary position, a guideway for the pins provided with resilient means to encounter the flat surfaces of the pins to rotate the latter axially to present such surfaces in drilling position during feeding of the pins in the guideway, and means to feed the pins 30 successively through the guideway with respect to the second named means. 35
  - 40 4. A drilling machine of the character specified comprising means to rotate and reciprocate a drill, supply means for pins having flat surfaces, a guideway for the pins,
- a movable block operative with relation to the guideway and provided with an inclined portion to encounter flat surfaces of the pins to rotate the latter to drilling position, and means to feed the pins successively through the guideway and with respect to said block. 45
5. A drilling machine of the character specified comprising means to rotate and reciprocate a drill, supply means for pins having flat surfaces, a movable member operative relatively to the drilling means, a block provided with an inclined portion to cooperate with surfaces of the pins to rotate the latter into drilling position, means upon said member for guiding said block, means to successively feed the pins through said guideway with respect to said block, and means to actuate said movable member. 50
6. A drilling machine of the character specified comprising means to rotate and reciprocate a drill, supply means for pins having flat surfaces, a movable member operative with relation to the drilling means, said member having a bar provided with a recess, a block operative in said recess and provided with an inclined portion to cooperate with flat surfaces of the pins to rotate them into drilling position, means resiliently pressing the block into pin-engaging position, said member having a portion to support and release the pins, and means to feed the pins successively past the block into drilling position. 55
7. A machine as set forth in claim 6, in which the block is provided with a pin and said member is provided with a slot receiving the pin for retaining the block in operative position respecting said member. 70 75

PETER MEYER.
